UNITED STATES PATENT OFFICE.

FRANK KINNEY, OF OAKDALE, PENNSYLVANIA.

CLAMP FOR DERRICKS.

1,127,450.

Specification of Letters Patent.

Patented Feb. 9, 1915.

Application filed July 28, 1914. Serial No. 853,752.

To all whom it may concern:

Be it known that I, FRANK KINNEY, a citizen of the United States, and resident of Oakdale, in the county of Allegheny and State of Pennsylvania, have invented a new and useful Improvement in Clamps for Derricks; and I do hereby declare the following, to be a full, clear, and exact description thereof.

10 My invention relates to oil-well derricks formed of pipe sections, and relates more especially to the clamps for clamping the sections of pipes at their joints and for providing for the connection of the girts and 15 braces to said clamps by means of which the derrick is built up and braced.

In the accompanying drawing Figure 1 is a view of a lower portion of a derrick showing my invention applied thereto; Fig. 2 is 20 a perspective view of the clamp; and Fig. 3 is a sectional view of same, showing the pipe therein.

In the drawing, the numeral 2 designates the pipe-sections of suitable gage and diameter, the lower ends of said pipe-sections resting in suitable sockets 3. The pipe sections 2 are connected at their joints by the clamps 4 which form the subject matter of my invention. These clamps are preferably 30 formed of a piece 5 of wrought iron or steel of suitable gage. The metal is bent to form the tubular-portion 6 into which the pipe-sections are inserted, and the free ends 7 and 8 are brought up into parallel relation with 35 each other and contiguous, the end 8, however, being tangential to the curve of the tubular portion 6 and extending beyond the end portion 7 and forming the plate-portion 8a. The end portions 7 and 8 are provided 40 with the openings 9 through which the compression-bolts 10 pass for securing the clamp to the pipe-sections. It is apparent that due to the spring of the metal the drawing up on the compression-bolts 10 will act to force the 45 clamp tightly around the pipe sections, as indicated in Fig. 3. The plate-portion 8a has the openings 11 formed therein.

The plate 12 is secured to the tubular portion 6 of the clamp, said plate being tangential to the curve of the tubular portion 6 and attached by riveting, electric welding, or any other suitable manner, and said plate is provided with the openings 13.

When the clamp has been clamped on the pipe-sections by the compression-bolts, the 55 girts 14 and braces 15 are connected up to the clamps, as indicated in Fig. 1. The girts 14 are preferably tubular in form and connected by the bolts 16 to the middle openings of the openings 11 and 13 of the plates 60 8 and 12. The braces 15 are connected by bolts 17 to the upper and lower openings of the openings 11 and 13, as clearly indicated in Fig. 1.

By bending the metal piece 5 in the manner indicated, I provide the tubular-portion for the clamping of the clamp to the pipe-sections, and at the same time by extending the free end portion 8 to form the plate 8a in the manner illustrated I also provide for 65 the attachment of the girts and braces to this extension plate which forms one of the clamping members. In this way, I simplify the construction and at the same time provide a very strong and secure form of clamp. 75

What I claim is:

1. A clamp for connecting the pipe sections of derricks, comprising a piece of metal bent to form a tubular-portion, the free ends of the metal having openings, compression bolts engaging said openings, one of the free ends extending tangentially to the curve of said tubular-portion, and beyond the other to form a plate-portion having openings therein, and a plate tangential 85 to the curve of said tubular-portion extending out at right angles to said plate-portion having openings therein.

2. A clamp for connecting pipe sections of derricks, comprising a piece of metal bent 90 to form a tubular-portion, the free ends of the metal having openings, compression bolts engaging said openings, one of the free ends extending tangentially to the curve of said tubular-portion, and beyond the other 95 to form a plate-portion having openings therein, and a plate secured to said tubular-portion tangentially of said tubular-portion, and extending out at right angles to said plate-portion having openings therein. 100

In testimony whereof, I the said FRANK KINNEY have hereunto set my hand.

FRANK KINNEY.
